US00D998402S

(12) **United States Design Patent** (10) Patent No.: **US D998,402 S**
(45) Date of Patent: **** Sep. 12, 2023**

(54) **BREWING DEVICE**

(71) Applicant: **Instant Brands Holdings Inc.**,
Downers Grove, IL (US)

(72) Inventors: **Chunshik Kim**, San Jose, CA (US);
Tyler Brunner, Durand, WI (US);
Daniel Wodka, Riverside, IL (US)

(73) Assignee: **Instant Brands Holdings Inc.**,
Downers Grove, IL (US)

(**) Term: **15 Years**

(21) Appl. No.: **29/820,070**

(22) Filed: **Dec. 20, 2021**

(51) LOC (14) Cl. **07-01**

(52) U.S. Cl.

USPC **D7/306**

(57) **CLAIM**

The ornamental design for a brewing device, as shown and described.

DESCRIPTION

FIG. 1 is a perspective view of a brewing device showing the new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines are for environmental purposes only and do not form any part of the claimed design.

1 Claim, 7 Drawing Sheets
